(57) **CLAIM**

The ornamental design for a pump module for printing machine as shown and described.

DESCRIPTION

Figure 1.1 is a bottom plan view of the pump module for printing machine, showing our new design;

Figure 1.2 is a left-side elevation view thereof;

Figure 1.3 is a back, left-side perspective view thereof;

Figure 1.4 is a back elevation view thereof;

Figure 1.5 is a front elevation view thereof;

Figure 1.6 is a right-side elevation view thereof;

Figure 1.7 is a top plan view thereof; and,

Figure 1.8 is a front, right-side perspective view thereof.

The broken lines shown in the drawings represent portions of the article that form no part of the claimed design.
